UNITED STATES PATENT OFFICE.

VALENTINO CASAZZA, OF NEW YORK, N. Y.

WINDOW-SCREEN.

1,053,010.

Specification of Letters Patent. Patented Feb. 11, 1913.

Application filed July 25, 1912. Serial No. 711,403.

To all whom it may concern:

Be it known that I, VALENTINO CASAZZA, a subject of the King of Italy, and a resident of the city of New York, borough of 5 Manhattan, in the county and State of New York, have invented a new and Improved Window-Screen, of which the following is a full, clear, and exact description.

Among the principal objects which the 10 present invention has in view are: to provide means for permitting and for inducing the escape of flies from the rooms provided with the screens; to provide means for reversing the operative position of the screen; 15 and to provide traps for the capture of flies when passing through the screen.

Reference is to be had to the accompanying drawings forming a part of this specification, in which similar characters of reference indicate corresponding parts in all 20 the views, and in which—

Figure 1 is a perspective view of a window screen constructed and arranged in accordance with the present invention, part 25 of the netting having been removed to show the construction of parts otherwise concealed; Fig. 2 is a vertical section, on an enlarged scale, of a screen constructed in accordance with the present invention; Fig. 3 is a similar section, showing the screen in an operative position the reverse of that 30 shown in Fig. 2; Fig. 4 is a detail view in perspective of a corner fragment of the screen when provided with a trap for capturing insects.

As seen in the accompanying drawings, the screen, when constructed in accordance with the present invention, is provided with an outer frame 9 and an inner frame 10. 40 The frame 9 is, as a rule, stationarily mounted in the window frame, and may be constructed to fit the same. The inner frame 10 is pivotally connected, by means of pins 11, with the outer frame 9. By means of 45 this construction, the frame 10 may be reversed whenever it is desired. The frame 10 is furnished with a covering of wire gauze 12, of the kind usually provided for window screens. The upper and lower rails 50 of the frame 10 are provided with flared recesses 13, each recess being provided with a perforation 14.

When adjusting the gauze 12 to the frame, care is exercised not to cover the perforations 14, these forming the passages through 55 which the insects pass when leaving the

apartment. By placing the perforations 14 along both the upper and lower edges of the frame, provision is made whereby when the screen is inverted, the exit perforations are 60 to be found at the top of the screen. These perforations are so inconsiderable that flies or insects, as a rule, will not enter from the outside, though they will pass from the inner to the outer side, being directed by the 65 increased light which is on the outside of the screen.

Each of the stiles of the frames 10 is scarf'd or cut to form benches 15 having inclined surfaces upon which are fastened 70 ribbons formed of wire gauze. The ribbons 16 are inclined from the vertical, and the upper and lower edges are lapped, as best seen in Figs. 2 and 3 of the drawings. The arrangement of the ribbons 16 is such that 75 an insect crawling up the face of one of said ribbons passes to the inside of the ribbon next above.

The theory of operation of the herein-described screen is based upon the tendency of 80 insects, when on a vertically-disposed surface, to crawl upward thereon. When the ribbons 16 are in the usual operative position, where the said ribbons are turned toward the room in the windows of which they 85 are placed, the insects, alighting on the surface of the ribbons and crawling upward, pass into the space between said ribbons and the gauze 12. If, in their confusion, they fly backward from the gauze 12, they alight 90 upon the upwardly-inclined surface of one of the ribbons 16, and crawl to the upper edge thereof. Instead of crawling down on the reverse side of said ribbon, the instinct 95 of the insect is to fly from the upper edge and, in alighting, to then again, following its tendency, crawl in an upward direction. In due course, the insect follows the gauze 12 upwardly, and passes through one of the recesses 13 and one of the perforations 14 100 thereof, to the outer air.

For the purpose of cleaning the screen, the frame 10 may be rotated on the pins 11, to dispose the gauze 12 on the side of the frame toward the interior of the room, as 105 shown best in Fig. 3.

When it is desired to trap the insects, the gauze 12 is provided with one or more openings 17 adjacent the upper edge of the frame 10, and over the openings 17, a suitable trap, such as the cage 18, is suspended. By any 110 suitable means, such as a hook 19, the trap or

cage 18 may be suitably baited to induce the insects to pass within the interior of said trap, from which they cannot free themselves. The cage 18 is of a character which 5 will permit the removal thereof, to be submerged in water or otherwise handled for the destruction of the insects.

Having thus described my invention, I 10 claim as new and desire to secure by Letters Patent:—

1. A window screen, comprising a stationary outer frame fitted to the window opening: an inner frame fitted to said outer frame and movable therein; pivotal mountings for said inner frame; a gauze covering for said inner frame; means for forming passages at the upper edge of said inner frame opening at both sides of said screen; and a plurality of lapped gauze sections 15 stretched horizontally on said window frame at the side thereof opposite that having said gauze covering, said sections being spaced apart to afford passages leading into the space between said sections and said covering.

25 A screen such as described, comprising

an outer holding frame; an inner frame pivotally mounted in said outer frame, said inner frame comprising horizontally-disposed rails having angular recesses formed 30 therein to open at one side of said inner frame, and vertical stiles having inclined benches formed thereon at the side of said frame opposite that from which the said recesses open; a gauze covering mounted 35 upon said inner frame at the side having the recesses, said covering being limited to expose said recesses; and a plurality of horizontally-extended gauze sections mounted on said benches, said sections overlapping 40 and separated to form passages between said sections, leading upwardly to the interior of the frame between said sections and said gauze covering.

In testimony whereof I have signed my 45 name to this specification in the presence of two subscribing witnesses.

VALENTINO CASAZZA.
